CLOTHES WASHING MACHINE

Noble H. Watts, Bridgeport, Conn., assignor to
General Electric Company, a corporation of
New York

Application December 1, 1930, Serial No. 499,395

9 Claims. (Cl. 259—101)

The present invention relates to clothes washing machines of the type having an oscillating agitator, which are intended more especially for domestic use. Machines of this type have the advantage of rapid operation but against this is the fact that the agitators heretofore used cause undue wear of the fabrics and are also liable to injure them.

The object of my invention is the provision of an improved washing machine of the agitator type, which has the advantage of rapidly and thoroughly washing fabrics without appreciable wear thereof or injury thereto. A further object of my invention is the provision of an improved agitator.

For a consideration of what I believe to be novel and my invention, attention is directed to the accompanying description and the claims appended thereto.

In the attached drawing, which is illustrative of my invention, Fig. 1 is a view in elevation of a washing machine with a part of the tub broken away; Fig. 2 is a top plan view of the agitator; Fig. 3 is a bottom plan view; Fig. 4 is a vertical axial section; Fig. 5 is a section taken on line 5—5 of Fig. 4, and Fig. 6 is a section taken on line 6—6 of Fig. 4.

In the drawing, 6 indicates a metal base which contains an electric driving motor and the mechanism actuated thereby for oscillating the agitator 7. Mounted on the base is a suitable tub 8, which in the machine illustrated is designed to contain approximately sixteen gallons of water. The wringer has been omitted as it is not necessary to an understanding of the invention. The motor and the mechanism for transmitting its motion to the agitator have also been omitted for the same reason. For the purposes of this case it is sufficient to say that any suitable type of mechanism may be employed which will impart to the agitator an oscillatory movement of approximately 200°.

The agitator is purposely made relatively high for reasons to be explained more fully later on, its upper end extending a short distance above the predetermined level of the suds water in the tub, for example, approximately one and three-quarters inches. The agitator is cast in a single piece in order that it may be rugged and also to avoid joints and fastening means. All of the surfaces with which the fabrics engage are made smooth to avoid injury thereto. In order to reduce weight the agitator may with advantage be made of aluminum. It comprises a hollow body having a base or disk 9 and three radial blades 10 which

rise vertically from the disk and terminate in a hub 11, the upper end of which is smooth and well rounded at its outer edge to prevent injury to the fabrics. Starting at the top of the agitator the outer edge of each blade gradually diverges from the axis toward the lower end. An angle of approximately 20° with the axis has been found to be satisfactory. As each rib approaches the disk, and beginning about half way down, it diverges much more rapidly from said axis than does the upper part and terminates in a well rounded end 10' which projects beyond the peripheral surface of the disk. At the upper or hub end where the blades merge therewith, they are made slightly thicker as indicated at 12 and taper as they descend so as to avoid corners, and therefore pockets, into which the fabrics would not move. The wall 13 of the body between each pair of blades is gradually curved from the hub so as to avoid the formation of pockets and to afford a smooth easy path for the fabrics as they move downward due to the pulling action of the agitator. Starting at the top, the wall extending between each pair of blades presents an inwardly curved surface, the radii of which gradually increase toward the bottom as best illustrated by the dotted lines 14 and 15 in the plan view Fig. 2 and the sectional views Figs. 6 and 5. The dotted lines correspond in position to the sections 5—5 and 6—6. At the bottom the wall merges by an easy curve 16 into the disk which is practically flat on its upper surface. Fig. 4 being an axial section, the curvature between the sides of the blades above the curve 16 is not shown. From the foregoing it will be seen that the surface of the body between each pair of blades is curved in two ways, one from blade to blade and the other downwardly to the disk.

As an illustration, but not as a limitation, of my invention, the radius of the curved wall near the disk and indicated by the dotted line 14 may be of the order of 10 $\frac{1}{2}$ inches and the radius of the curved wall at the top may be of the order of 4 $\frac{3}{4}$ inches. Due to this arrangement it will be observed that the curvature gradually becomes flatter from the top towards the bottom. As will be seen from the various figures the sides of the curved wall between blades are tangent or substantially so to the sides of the blades with the result that the surface presented is smooth and of easy curvature so that the fabrics will move readily over them from the top to the bottom, and all pockets or dead spaces between blades are avoided. The impeller is hollow as best shown in Fig. 4 so as to reduce the weight thereof and thus reduce 65

the inertia of the moving parts as the direction of oscillatory movement is reversed by the actuating mechanism. The upper end of the impeller is provided with splines or keys 17 which cooperate with similar devices on the actuating shaft 18. A steady bearing is also provided which comprises a bronze bushing 19 which makes a forced fit with the body and has a Babbitt lining 20.

By reason of the above described curved surfaces between the blades, bending or flexing of the fabric is obtained and also rubbing of the fabrics one on the other. The maximum washing zone is at or near the bottom of the impeller and between this and the top various degrees of washing are effected. By reason of the described curved surfaces between blades the rubbing action is made such that it will not injure fine fabrics.

Experience with the impeller demonstrates that the fabrics contained in the body of water in the tub near the top or water level move downward over the said curved surfaces to the bottom and are discharged radially toward the side of the tub and then move upwardly to the water level and then inwardly, after which the cycle is repeated. This movement of the fabric is due to the current of water caused by the progressive difference in diameter or size of the parts of the impeller from the top to the bottom. Experience has further demonstrated that due to the presence of said curved surfaces, to the shape and arrangement of the blades, and to an oscillation of the impeller of approximately 200°, tangling of the fabric, which is so objectionable in other washing machines of the agitator type, is practically nil. The lower end portions of the blades which project beyond the bottom disk are important because they cause the fabrics to be swished through the water as well as acting as means to discharge them radially.

Because of the oscillating movements of the agitator the movements of the fabrics in the suds water are complex but in general it may be stated that in addition to oscillating movements there is a decided movement of the fabrics from the inner wall of the tub at all points at approximately the water level toward the center, thence downward along the incurved walls of the agitator, then an outward unimpeded radial movement along the bottom of the tub to the inner wall, and thence upwardly, also unimpeded, to the top, or water level, when the cycle is repeated. The presence of the blade tips and the constantly enlarging area from the agitator prevents tangling or twisting of the fabrics. The improved washing action is due among other things to the fact that the upper end of the impeller terminates at or slightly above the level of the water and hence the impeller exerts a downward pull on the fabrics from the water level to the bottom, this being in contra-distinction to a low impeller which when in service is completely covered by the fabrics. This results in a circular rolling movement of the fabrics in passing from one zone to another, and a free continuous return movement. As the fabrics move downwardly they rub on each other as well as on the surfaces of the impeller and are flexed or bent in their passage from the top to the bottom which action assists in the washing operation.

Viewed from another aspect, it will be seen that the improved agitator comprises three triangular shaped concave side walls 13 which merge into each other at their side edges to form

the radial blades 10 and which merge into the bottom disk with an easy curve 16. Thus, each side wall has a double concave curvature, i. e., a concave curvature in a horizontal plane and a concave curvature in a vertical plane. This arrangement provides smooth continuous concave surfaces for effecting movement of the clothes being washed whereby uniform action on all the clothes and even distribution of the clothes in the tub is obtained.

What I claim as new and desire to secure by Letters Patent of the United States, is:

1. In a fabric washing machine, the combination of a tub adapted to contain a body of water, an agitator for moving the fabric within the tub, said agitator comprising a body, the top of which approximates the level of the water in the tub, a plurality of spaced blades extending radially from the body, the portion of said body between each two blades being inwardly curved from blade to blade to form a substantially continuous concave surface the radius of the surface increasing from top to bottom with the sides thereof substantially tangential to the sides of the blades, and a shaft for oscillating the agitator.

2. An agitator for a fabric washing machine comprising a hollow body having a disk at the bottom and gradually decreasing in size from the disk to a hub at the top, a plurality of radially disposed blades carried by the body and extending from the hub to the disk the outer edges of the blades gradually tapering outwardly from top to bottom, the outer wall of the body between each two blades being inwardly curved from blade to blade to form a substantially concave surface with the sides thereof tangential to the sides of said blades the radius of the curve gradually increasing from top to bottom, the lower end of said outer wall being connected by a curved surface to the disk, said surface being substantially tangential to the upper surface of the disk.

3. An agitator for a fabric washing machine comprising a unitary structure having a hollow body with a disk at the bottom and a hub at the top, spaced blades formed integral with the body and extending in radial planes from the hub to the disk, said blades decreasing in thickness from the upper end thereof toward the disk, the surface portion of the body between each pair of blades being curved upwardly as it rises from the disk and also curved from blade to blade so as to form a substantially concave surface, the last mentioned portion of said curved surface being tangential to the vertical sides of the blades and gradually becoming flatter from the top toward the disk.

4. An agitator for a fabric washing machine comprising a hollow body having a small hub at the top and a large disk at the bottom, three equally spaced radial blades formed integral with the body, the lower ends of said blades projecting beyond the peripheral surface of the disk, the portion of the body between each two blades and the disk being curved inwardly toward the axis of the body and forming an uninterrupted concave surface which extends substantially throughout the length of the agitator with the sides of said portions tangentially arranged with respect to the sides of the blades.

5. An agitator comprising a base plate and a plurality of triangular shaped concave side walls which merge into each other at their side edges to form blades which taper outwardly from top to bottom and increase in thickness from their edges

inwardly, said side walls merging into the base plate at their lower edges with a smooth even curve.

6. An agitator comprising a base plate and three triangular shaped concave side walls which merge into each other at their side edges to form blades extending from the base plate to substantially the top of the agitator, said blades tapering outwardly from top to bottom and increasing in thickness from their edges inwardly, said side walls merging into the base plate at their lower edges with a smooth even curve.

7. An agitator comprising a top hub of small diameter, a base plate of relatively large diameter, and a plurality of triangular shaped side walls connecting them, said side walls being concave in a transverse plane and merging into each other at their side edges to form vertically extending blades and said side walls being concave in a vertical

plane and merging into the hub at their upper ends and into the base plate at their lower ends.

8. An agitator comprising a base plate and a plurality of concave side walls, the edges of which taper gradually inwardly from the bottom to the top and which merge into each other at the side edges to form blades which taper outwardly from top to bottom and increase in thickness from their edges inwardly, said side walls merging into the base plate at their lower edges with a smooth even curve.

9. An agitator for washing machines which comprises a pyramidal body portion having its sides curved inwardly completely across the same about substantially vertical axes, said sides being curved along sweeping arcs and joined along well rounded edges.

NOBLE H. WATTS.
